UNITED STATES PATENT OFFICE.

CLAUDE STEWART KELLUM, OF INDIANAPOLIS, INDIANA, ASSIGNOR OF
ONE-HALF TO JAMES ALBERT HAYES, OF KOKOMO, INDIANA.

LETTER-PACKAGE TIE.

SPECIFICATION forming part of Letters Patent No. 749,985, dated January 19, 1904.

Application filed March 24, 1903. Serial No. 149,257. (No model.)

To all whom it may concern:

Be it known that I, CLAUDE STEWART KELLUM, a citizen of the United States, residing at Indianapolis, in the county of Marion and State of Indiana, have invented certain new and useful Improvements in Letter-Package Ties, of which the following is a specification.

This invention relates to improvements in ties for securing letters in packages such as are made up by postal clerks in the mail-service; and the object is to provide a rigid and substantial form or back having a cord fixed thereto, by means of which the letters, post-cards, and such other matter as may be destined for the same terminal or way point may be tied together and secured to said rigid back piece.

The object of the invention is to provide an efficient and quickly-manipulated fastening for the free end of the cord after the tie is made and to provide means for removably securing the cord to the back piece.

I accomplish the objects of the invention by the mechanism illustrated in the accompanying drawings, in which—

Figure 1 is a plan view of a package secured with my improved tie; Fig. 2, a section on the line 22 of Fig. 1; Fig. 3, a detail in plan view of the center of the back piece with the locking-plate removed; Fig. 4, a section of the back piece on the line 44 of Fig. 1; Fig. 5, a detail in partial section of the end loop of the tie-cord, showing the manner of its construction; Fig. 6, a detail in plan view showing a modified attachment of the permanently-sealed end of the tie-cord, and Fig. 7 a detail showing a second modified cord-fastening.

Like characters of reference indicate like parts throughout the several views of the drawings.

8 is the back plate of any suitable dimensions, generally approximating in size and shape the size and shape of the average envelop or post-card. It may be made out of any suitable material which will combine the necessary rigidity and strength with lightness—such, for example, as brass, iron, steel, aluminium, and the like in sheet form. The

mail-matter for a given destination will be stacked upon this plate and secured to it by means of a cord 9.

Where very thin sheet metal is used for the body 8, it will be preferable to stiffen it by forming the marginal bead 10 by bending the edge in the manner shown in Fig. 4. This also insures a smooth finish, which prevents injury to the mail-matter by contact with the edge, which would result were the edges left thin, and therefore comparatively sharp. Where a body of aluminium is used, the permissible thickness of so light a metal will allow the edges to be rounded without the bead formation.

A depression 11 is formed at the middle of the back piece 8, and at the center of the depression is a post 12, (preferably a metal rivet,) the base of which is securely seated and fastened to the back 8. To the outer end of the post is secured the hood or cap 13, which is a circular disk with a central perforation to receive the post, the end of the latter after insertion being riveted to prevent the removal of the disk. The depth of the depression 11 is such as to let the outer face of the disk in approximately flush with the outer surface of the back 8. The cord 9 has the end loop 14, which is passed around the post 12 between the cap 13 and the back 8, thereby forming an attachment which allows the cord to be shifted around the post, so as to start at right angles in any direction from it. Radiating from this central depression and at right angles to each other are four corrugations 15, which form longitudinal and lateral channels across the body 8 to receive the cord 9 when the latter is wrapped around a package of letters in the manner shown in Figs. 1 and 2. The channels depress the cord below the outer surface of the body 8, so as not to engage any of the parts of adjacent packages. A when numbers of them are thrown together in the promiscuous and hurried manner of the mail-service.

The loose end of the cord 9 is secured by slipping it under the cap 13 either with or without giving it a turn or more around the

post 12, and to make the engagement of the cord more positive between the cap and the body 8 I provide the radial depressed corrugations 16 in the cap and the raised corrugations 17 at the bottom of the depression 11 under the cap 13. This formation is shown in Fig. 2. These radial corrugations engage the cord, so as to prevent its accidental release, but at the same time permitting the easy introduction and removal of the cord when taken hold of by the operator and moved laterally of the cap with a swinging or rotary movement of the hand holding the cord. The area of the depression 11 will be such as to allow of the free introduction and removal of the cord.

A slot 18 will preferably be made in one end of the body 8 to exhibit the label which indicates the route or destination of the pack-

age.

The loop at the inner end of the cord 9 will preferably be held by means of a Y-shaped tubular holder, one of the tubular arms 19 of which will contract outwardly in diameter to receive the end of the cord, which will be prevented from complete movement through the arm by the wedge 20 and barbs 21. The body of the cord will then be threaded through the remaining portion 22 of the holder in the manner shown in Figs. 3 and 5 to form the loop.

In the modification shown in Fig. 6 the cord is threaded through a transverse perforation in the post 12^a and held by a knot in the end of the cord.

In the modification shown in Fig. 7 the end of the cord will be held by an outwardly-tapering tube 23, which has an eye 24 at its outer end to engage the post 12^b.

My invention is capable of various modifications without departing from its spirit, and I therefore do not limit myself to the forms shown.

What I desire to claim is—

1. In a device for the purpose specified, a 45 post, a plate on which the post is mounted, having corrugations radially of the post, a flexible tie secured at one end to the post, and means for removably securing the opposite end of said tie after the tie has been wrapped 50 around the articles to be bound, said means comprising a radially-corrugated disk mounted on the said post.

2. In a device for the purpose specified, a plate having a middle depression, a post secured to the plate in said depression, a cap mounted on the post, and a flexible tie having one end fastened to the post and its opposite end detachably secured by being caught between the cap and plate after being wound 60 around the articles to be bound.

3. In a device for binding packages of mail-matter, a plate having longitudinal and transverse depressions, a locking-plate mounted below the outer face of the plate, a flexible tie 65 secured to the plate at one end and adapted to lie in said depressions when wrapped around the package and to be removably secured at its opposite end by introduction between the locking-plate and the first plate.

4. In a letter-tie, a plate having a middle depression and centrally-located longitudinal and transverse channels leading across the plate from said depression, a radially-corrugated disk mounted in said depression and a 75 tie the wrappings of which are adapted to be laid in said channels and the loose end of the tie being adapted to be temporarily fastened between the plate and the corrugated disk.

In witness whereof I have hereunto set my 80 hand and seal, at Indianapolis, Indiana, this 13th day of March, A. D. 1903.

CLAUDE STEWART KELLUM. [L. s.]
